UNITED STATES PATENT OFFICE.

CHARLES COLE POWERS, OF KERNVILLE, CALIFORNIA.

ELECTRIC LOCOMOTIVE.

1,341,243.

Specification of Letters Patent.

Patented May 25, 1920.

Application filed December 9, 1919. Serial No. 343,656.

To all whom it may concern:

Be it known that I, CHARLES C. POWERS, a citizen of the United States, residing at Kernville, in the county of Kern and State 5 of California, have invented a new and Improved Electric Locomotive, of which the following is a specification.

My invention has reference to locomotives and particularly to electric locomotives, and 10 has for its purpose to provide an improved means for transmitting the power from the motor for actuating the side rods that connect with the driving wheels, which, in the usual construction of locomotives are linked 15 with and actuated by the steam shifted piston rod.

More specifically, my invention comprehends an improved arrangement of transmission devices connected with and adapted 20 for applying rotation to the driving wheels and so coupled with a single electric motor, so positioned, with respect to the driving wheels at each side of the engine, that the power of the said single motor may be transferred to the driving wheels in a manner 25 resultant in the development of an effective traction effort, when running under ordinary or high speeds.

The drawing hereto annexed, illustrates 30 diagrammatically a general arrangement of the parts constituting my improvement and in which:

Figure 1 represents in side elevation a locomotive equipped with my arrangement 35 of motor driven power transmission connections that join with the driving wheels.

Fig. 2 is a plan view of my invention.

In carrying out my invention, an electric motor 1 is suitably mounted within a cab 2 40 indicated in dotted lines on Fig. 1. The motor shaft 1^a, at its projected end, carries a worm gear 3 which may be formed with or otherwise fixedly connected with the said shaft.

45 The power transmission connections that join the motor or driving gear 3 with the engine drivers or wheels 4 (of which a number are shown having the usual link connections 40-40) and which constitute the 50 essential feature of my invention, comprise a driven shaft 5 that is journaled in any approved manner in suitable bearings (not shown), and which extend transversely, with respect to the motor, as is best indicated in Fig. 2, by reference to which it will

be observed that the shaft 5, midway its length, has an affixed worm gear 6 that meshes with the motor shaft worm gear 3.

As the transmission devices, at each side, are constructed and operated alike, relatively to their respective sets of driving wheels 4, a detailed description of one set of such connections will be sufficient for both.

7 designates a disk fixedly mounted on the 65 outer end of the drive shaft 5 and 8 is a wrist or crank pin attached to the disk.

In my arrangement of transmission mechanism, the rotary motion of the disk 7 is transferred into a reciprocatory motion 70 for impelling the slide rod 9, which acts as a substitute for the usual steam chest actuated piston rod and which, in my construction, is also pivotally joined to the outer or main driving wheel 4. 75

By referring more particularly to Fig. 1, it will be noticed, the outer end of the rod 9 is pivotally joined to the lower end of, what might be termed a draw bar 10, since the motive power is transferred from it 80 directly to the rod 9, the latter receiving its impelled motion from the bar 10, the same as if it were actuated through connection with the usual steam chest.

The draw bar 10 includes a crank-like portion 11 and has a slotted upper end 12, the latter being connected to the crank wrist pin 8 on the disk 7. 85

At the angled portion, the bar 10 is rockably mounted on a fulcrum member or shaft 90 13 that extends crosswise of the framing, see Fig. 2.

From the foregoing description taken in connection with the drawing, the complete construction, the manner of its operation 95 and the general advantages of my construction of electric locomotive will be apparent to those skilled in the art to which it appertains.

Assuming the engine to be running and the disk 7 as turning in the direction of the arrow thereon, the rotary disk motion develops the oscillatory motion to the draw bar 10 in the direction of the arrows thereon, and further assuming the crank portion of 105 the said bar 10 to be now moving in the direction of the arrow α , the rod 9 would now be impelled in the direction of the arrow γ , and the links 40 being above the axes of the drivers 4 will be transmitting 110

rotation to the drivers in the direction indicated under the now forward thrust of the bar 9 until the links 40 pass the dead or horizontal centers of the drivers, when the 5 rotation of the drivers is continued by the now backward pull or thrust of the bar 9.

What I claim is:

1. In a locomotive, an electric motor driven rotatable shaft, a transmission connecting the shaft and the driving wheels, said transmission including an oscillatable draw bar actuated through the rotary motion of the motor driven shaft, and a reciprocably operating bar that connects the oscillatable draw bar with one of the driving wheels.
2. In a locomotive, a motor driven shaft, a transmission connecting the shaft and the driving wheels, said transmission including an oscillatable draw bar actuated through the rotary motion of the motor driven shaft, and a reciprocably operating bar that connects the oscillatable draw bar with one of the driving wheels, the said oscillatable

draw bar including a slotted upper end and 25 a crank or wrist pin connection.

3. In a locomotive, a motor driven shaft, a transmission connecting the shaft and the driving wheels, said transmission including an oscillatable draw bar actuated through 30 the rotary motion of the motor driven shaft, and a reciprocably operating bar that connects the oscillatable draw bar with one of the driving wheels, the said oscillatable draw bar including a slotted upper end and 35 a crank or wrist pin connection, the said transmission including a crank disk on the shaft, an oscillatable draw bar actuated by rotation of the said shaft, the said bar including an upper slotted member that engages the crank of the aforesaid disk and a lower crank shaped end, and a reciprocably operating bar that pivotally connects at one 40 end with the crank end of the draw bar and pivotally joins at its other end with one of 45 the driving wheels.

CHARLES COLE POWERS.
